No. 36,647.

Patented November 24, 1903.

UNITED STATES PATENT OFFICE.

FRANCIS J. TORRANCE, OF ALLEGHENY, AND JOHN F. WHITEHEAD, OF NEW BRIGHTON, PENNSYLVANIA.

DESIGN FOR A LAVATORY.

SPECIFICATION forming part of Design No. 36,647, dated November 24, 1903.

Application filed November 17, 1902. Serial No. 131,786. Term of patent 14 years.

To all whom it may concern:

Be it known that we, FRANCIS J. TORRANCE, residing at Allegheny, in the county of Allegheny, and JOHN F. WHITEHEAD, residing at New Brighton, Beaver county, Pennsylvania, citizens of the United States, have invented a new, original, and ornamental Design for Lavatories; and we do hereby declare the following to be a full, clear, and exact specification of the same, reference being had to the accompanying drawings, forming a part thereof.

Our design for a lavatory is shown in the accompanying drawings, in which—

Figure 1 is a perspective view, and Fig. 2 is a top plan view, of the lavatory.

What we claim as our invention is—

The ornamental design for a lavatory herein shown.

In testimony whereof we affix our signatures in presence of two witnesses.

FRANCIS J. TORRANCE.
J. F. WHITEHEAD.
